UNITED STATES PATENT OFFICE.

GUIDO TALLEI, OF ROME, ITALY.

MIXED AIRSHIP PROVIDED WITH PARACHUTE.

Application filed October 12, 1927, Serial No. 225,721, and in Italy October 15, 1926.

The present invention concerns a novel type of airship with mixed sustentation and provided with a parachute, that is an airship provided with supporting surfaces in such a manner as to obtain as a result a flying machine which while possessing all the advantages of the usual airplanes and airships assembled together eliminates as far as possible the inconveniences of both types, the supporting surfaces being arranged in such a manner that they can act as parachutes when the necessity arises.

The airship according to the present invention consists substantially of a central hollow body of elongated shape, said hollow body having symmetrical carrying surfaces externally disposed and attached to the sides and top thereof.

The central body consists of a gas envelope of aluminium sheet or of any other light metal sheet; said envelope is carried by a supporting and stiffening frame and contains in its interior air heated by means of the exhaust gases of the engines, so as to produce a statical lifting power to which, during the flight is added the dynamical lifting power due to the pressure which the external air develops against the carrying surfaces, which act in the same manner as the wings of the usual airplane and, when the necessity arises, also as parachutes.

In the annexed drawing, which shows by way of example and schematically a practical embodiment of the invention:

Fig. 1 is a top view of the airship.
Fig. 2 is a side view.

The Figures 3 and 4 are cross sections according to the lines X-X and Y-Y of Fig. 1, respectively.

Figure 3 is a horizontal section through the longitudinal axis.

Figure 4 is a vertical longitudinal section of the tail end drawn to enlarged scale.

Figure 5 is a vertical cross-section on the line X-X of Figure 1.

As shown in the drawing the airship according to the invention substantially consists of an envelope 25 of thin corrugated metal sheet covered by an outer skin 24 which is of thin smooth metal sheet. Said double envelope which constitutes a strongly insulating wall has the general appearance of the body of a bird, the mouth of which is seen at 19, the head at 20 and the neck at 21. At the sides are the two cars 7 carrying

three pairs of propellers, one pair of which 8 are pulling while the other two pairs 26 are pushing. The wings, or supporting surfaces are circular in shape and consist of two superposed discs, 3', 3'', which can act 60 also as parachutes.

At the rear end, that is at the stern is provided another supporting surface formed by two superposed discs 6', 6'' which are movable together in the longitudinal direction 65 under the control of the pilot, by means of a rigid or flexible transmission of any convenient type. Figure 4 shows that said surfaces are carried by a rack 30 engaging a pinion 31 which can be rotated in either 70 direction by means of a transmission 32, so that the pilot can shift the rack and said second supporting surfaces longitudinally as desired. The steering surfaces comprise a vertical disc 9 mounted rotatable around a 75 vertical axis 36 passing through the centre of the discs 3', 3''. Axis 36 has positioned on its lower extremity a chain wheel 34 which may in turn be rotated by a common transmission 35. Three vertical discs 5 are 80 mounted under the tail of the machine and they are also rotatable around vertical axes which lie all in the middle plane of the machine.

The axes 33 carry chain wheels 34, which 85 may be in turn rotated by a common transmission 35.

In order to impart to the gas envelope the necessary resistance its body 23 is mounted upon ring shaped frames 11 conveniently 90 distanced and connected by means of stiffening and supporting spokes 22 to a central tube 10 extending for the whole longitudinal axis of the airship. This tube is closed at the fore end and freely open at the rear end 95 for the purpose which will be explained hereinafter.

In fact said tube has not only the purpose of acting as a hub for the attachment of the spokes 22 but is also intended to receive in 100 proximity of its fore end, the exhaust gases escaping from the engines placed in the cars 7. The exhaust gases thus flow through conduits 27 to the central tube 10 and heat strongly the air contained between the internal walls of the envelope and the external wall of the tube 10.

The increase of temperature thus obtained causes a rarefaction of the air contained in the envelope and therefore the production of 110

a certain amount of lifting power which contributes in lifting the airship. The buoyancy of the whole airship is considerably increased by the fact that both discs 3', 3" and 6', 6" are filled with a light gas, as helium for instance.

In the walls of the central tube 10 openings 28 may be provided through which the exhaust gases may escape in the interior 23 of the envelope. In this manner the lifting power can be notably increased because a higher temperature can be maintained in the interior of the envelope.

To the lifting power thus obtained is added the dynamical lifting power supplied by the two, or more, circular wings 3' and 3" before mentioned cooperating with the two discs 6', 6" at the rear. The main wings 3', 3" are kept rotating permanently, either by means of any convenient transmission connected with the propulsion motors, by independent motors 29 or by means of the action of the wind. This rotation diminishes the resistance to the forward movement and adds to the stability by reason of the gyroscopic effect. By reason of their circular shape the wings 3', 3" will act also conveniently as parachute surfaces in the case of an involuntary descent.

For steering purposes the action of the tail supporting surfaces 6', 6" can be changed by shifting them longitudinally forwards or rearwards in a manner hereinbefore explained.

The common bottom of the two cars 7 forms also a supplementary wing or supporting surface which adds to the dynamical lifting power.

The propulsive power is supplied by two sets of engines symmetrically placed in respect of the central body on board of the two cars, the hulls of which are conveniently shaped, in such manner as to allow the application of the several propellers 8, 26 to each one of them in the manner shown in the drawing.

Further a not negligible increase of the propelling power is due to the arrangement above mentioned that the exhaust gases escape in the axial direction at the rear end of the longitudinal conduit 10, the reaction of the jet supplying a useful component for the forward movement in the same way as it happens in a jet propelled ship.

The airship built and working in the manner above said possesses considerable advantages in comparison of the other airships of the same class already known, and of the airship which has formed the object of a precedent application, Serial N. 138,464 of the same inventor, inasmuch as the circular shape of the supporting surfaces, their rotatory motion, and the disc shaped steering surfaces arranged at the top and under the tail of the machine, all contribute to secure better penetration, greater stability and easier steerability.

Claims:

1. An airship with mixed sustentation, comprising an envelope containing air, internal combustion engines disposed on either side of said envelope, a hollow tube extending along the longitudinal axis of said envelope, a plurality of conduits leading the exhaust gases from said engines through said longitudinal tube and a plurality of hollow disc shaped carrying surfaces containing a light gas positioned on said envelope.

2. An airship with mixed sustentation, comprising an envelope containing air, internal combustion engines disposed on either side of said envelope, a hollow tube extending along the longitudinal axis of said envelope, a plurality of conduits leading the exhaust gases from said engines through said longitudinal tube, a plurality of main disc shaped supporting surfaces mounted co-axially on said envelope above said internal combustion engines and a plurality of auxiliary disc shaped supporting surfaces mounted co-axially above one extremity of said longitudinal tube.

3. An airship according to claim 2 having a means for rotating said main disc shaped supporting surfaces and a second means for shifting said auxiliary disc shaped supporting surfaces longitudinally.

4. An airship according to claim 2 having a plurality of vertically mounted steering discs capable of rotation about a vertical axis and a common control means for so rotating said steering discs.

In testimony whereof I have affixed my signature at Rome this twenty-seventh day of September, 1927.

GUIDO TALLEI.
